ATTORNEY

UNITED STATES PATENT OFFICE.

HENRY L. ARNOLD, OF DENVER, COLORADO.

CAR-COUPLING.

SPECIFICATION forming part of Letters Patent No. 378,228, dated February 21, 1888.

Application filed July 5, 1887. Serial No. 244,658. (No model.)

To all whom it may concern:

Be it known that I, HENRY L. ARNOLD, a citizen of the United States, residing at Denver, in the county of Arapahoe and State of Colorado, have invented certain new and useful Improvements in Self-Coupling Attachments for Railroad-Cars; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to self-coupling attachments for the ordinary draw-heads of railroad-cars.

The object of my invention is to provide a self-coupling attachment which may be readily attached to the ordinary draw-heads of railroad-cars without having to alter the same, and which will couple itself with an attachment like itself, or with the ordinary link held in the draw-head of another car, regardless of the existing difference in the height of the same.

20 A further object of my invention is to provide an inexpensive self-coupling attachment for railroad-cars, which will couple itself with another like itself, or with the ordinary link, and which may be adjusted to prevent its coupling, if desired.

25 My invention consists of a self-coupling attachment for ordinary draw-heads of railroad-cars having the combination, with a multiple link adapted to be held in the draw-head, of a vertically-adjustable pin having a series of hooks projecting from one of its sides adapted and arranged to have a vertical movement within the multiple links, whereby a link or 30 series of links passed into the multiple link may be held or relieved at the will of the operator.

In the accompanying drawings, Figure 1 is a vertical section through the center of two 35 draw-heads and two couplers connected. Fig. 45 2 is a side view of two of my attachments coupled together and attached to two draw-heads, which latter are shown in dotted lines. Fig. 3 is a top view of the same. Fig. 4 is a 50 vertical section through the center of one of

the multiple links. Fig. 5 is a side view of one of the gripping-pins. Fig. 6 is a top view of the same.

Similar letters refer to similar parts throughout the several views. 55

In the drawings, *a* represents the multiple link, which is formed, as shown, with a series of short links, *a'*, which are U-shaped, projecting forward from the upright sides *a*, and a single U-shaped link, *b*, projecting backward from the sides *a*. The inner sides of the links *a'* are formed in the center of the outer ends with a semicircular depression, *c*, and the upright sides are formed with circular depressions *d*. The sides of the links *a'* are parallel and are at 60 right angles with the depressions *d*. The outer ends of the links *a'* are V-shaped in order to guide them between the link or links of the opposite coupler. The gripping-pin *A* is formed as shown in Figs. 1, 5, and 6, and is 65 provided with a series of projecting hooks, *A'*. On the outer end of these are semicircular depressions *B*, corresponding with the depressions *c* in the multiple link, the two forming a circular way for the reception of the safety-pin 70 *E*, which may be introduced in certain emergencies—such as the breaking of a gripping-pin, &c. 75

In placing my self-coupling attachment on the draw-head of a railroad-car it is only necessary to place the link *b* in the draw-head *e*, after the manner of placing an ordinary link, and then passing the pin *f* through the link and draw-head, as shown in Fig. 1, after which the gripping-pin *A* is placed in the multiple 80 links, with the small eccentric-lever *g* (which is attached to the upper left-hand side of the pin by a pivot) in the position shown in Fig. 2. 85

When it is desired to uncouple one car from another, the lever *g* is turned to the position 90 shown in dotted lines, Fig. 2, which brings the long side of the eccentric below the center of the pivot and raises the gripping-pin out of the reach of the coupling-link, which may then be withdrawn, the lever *g* being brought 95 to its normal position, which allows the gripping-pin hooks to project down past the links, and as the opposite coupling-link is pressed against the hooks *A'* the pin *A* is lifted, and as the links pass beyond the hooks into the 100

multiple link the pin drops with the hooks over and inside the links, which prevents them from being withdrawn.

Having now fully described my invention, 5 what I claim as new, and desire to secure by Letters Patent, is—

1. A self-coupling attachment for ordinary draw-heads of railroad-cars having the combination, with the multiple link adapted to be held in the draw-head, of a vertically-adjustable pin having a series of hooks projecting from one of its sides adapted and arranged to have a vertical movement within the multiple link, whereby a link or series of links passed into

the multiple link may be held or relieved at 15 the will of the operator, substantially as described and set forth.

2. In a self-coupling attachment for railroad-cars, the combination of the multiple link *a* with the gripping-pin *A*, provided with an eccentric adjusting-lever, *g*, substantially as described and set forth.

In testimony whereof I affix my signature in presence of two witnesses.

HENRY L. ARNOLD.
